S. R. SVENDSGAARD

DISPENSING MACHINE

Filed June 14, 1923

FIG. 1

Inventor
Sverre R Svendsgaard

By, Herbert E. Smith

Attorney

Patented Apr. 14, 1925.

1,533,147

UNITED STATES PATENT OFFICE.

SVERRE R. SVENDSGAARD, OF TEKOA, WASHINGTON.

DISPENSING MACHINE.

Application filed June 14, 1923. Serial No. 645,243.

To all whom it may concern:

Be it known that I, SVERRE R. SVENDSGAARD, a citizen of the United States, residing at Tekoa, in Whitman County and State 5 of Washington, have invented certain new and useful Improvements in Dispensing Machines, of which the following is a specification.

My present invention relates to improvements in dispensing machines for use in store service, and especially designed for manual operation by the clerk behind the counter, for the purpose of vending packages of commodities, as for instance chewing gum, and similar articles usually packed in wrappers or cartons.

The primary object of the invention is the provision of an attractive device of this character including a vending cabinet in 20 which a variety of articles, for instance packages of chewing gum of various flavors or makes, may be encased, and from which a selected package may be ejected as desired. The invention consists in certain 25 novel combinations and arrangements of parts within the cabinet whereby the articles to be dispensed may be displayed in attractive manner and singly ejected by the operator, as will be hereinafter more fully described and claimed.

In the accompanying drawings I have illustrated one complete example of the physical embodiment of my invention wherein the parts are combined and arranged according to the best mode I have 35 thus far devised for the practical application of the principles of my invention.

Figure 1 is a perspective view of the vending machine showing the magazine or 40 receptacle portion of the cabinet with parts in dotted lines, and for convenience of illustration only one of several interior partitions and stack supporting-hangers is shown.

Figure 2 is a transverse, vertical, sectional view through the cabinet and casing for the operating parts of the device.

Figure 3 is an enlarged detail perspective view showing the relation of a stack-hanger or support to its complementary partition, several of which partitions divide the cabinet into stack-compartments.

Figure 4 is a perspective view of one of the stack hangers.

The cabinet 1 is of generally rectangular form made up of plates of glass for its

walls to present an attractive appearance and disclose the packages P that may be contained therein. A base 2 is utilized to support the cabinet and a casing 3 is fixed 60 to the clerk's side of the cabinet for enclosing the operating and ejecting devices.

The upper face of the base, within the cabinet is fashioned with a series of spaced, parallel grooves 4 adapted to receive the lower or bottom edges of a series of glass plates 5, which form partitions and divide the cabinet into a suitable number of compartments for the retention of stacks of packages P. The partitions terminate with their upper edges just below the top of the cabinet, and they extend to the front or purchaser's side of the cabinet to form a series of discharge openings D between the lower edge of the glass front plate of 75 the cabinet and the base 2. At the upper rear corner, and within the cabinet a metal bracing plate 6 is provided which extends along the interior of the cabinet from side to side. This bracing plate is fashioned with a series of notches 7 alined with the series of grooves 4 in the base and the notches are designed to receive the rear edges of the series of spaced partitions 5 and hold them in proper spaced position. 80

The partitions are thus confined within the cabinet in the grooves and notches, against the rear wall 8 of the cabinet and retained in proper position to form the compartments for the stacks of commodities. 90 This combination and arrangement of parts provides for a simple and inexpensive, but at the same time effective structure, which may be assembled with facility. The top plate of the cabinet may be removed for the purpose of filling or charging the emptied compartments, and suitable means may be employed for locking the top on the cabinet.

For supporting or suspending the stacks 100 of packages within their compartments I utilize in each compartment a suspending device or stack-hanger 9, which is preferably of metal and fashioned at its upper end with a suspending hook 10 and at its lower end with a bottom flange 11. As shown the hook is twisted at an angle to the plane of the body of the hanger to fit over the top edge of a partition, and the flange 11 at the bottom of the hanger is bent forwardly 105 at right angles to the body of the hanger, or at the proper angle to support a packet 110

on end in vertical position, as indicated in Fig. 1 and also in Fig. 2 in dotted lines. It will be noted particularly in Figure 2 that the hook of the hanger is offset from the body of the hanger at the side of the hanger opposite to that from which the flange 11 projects. Thus in storing the packages or packets in the compartments the hanger is moved toward the front wall of the cabinet and two or more packets P are stood on end, standing on the flange 11 between the hanger and the front wall of the cabinet. In this position the labels on the standing packets may readily be observed by the purchaser and the contents of the packets identified. The supporting flange 11 terminates just above the top wall of the discharge opening D, and the hanger, with its two supported packets, is held in vertical position while the stack of packets is placed in the compartment at the rear of the hanger. The lowermost packet of the stack rests horizontally on the base and the ends of the superimposed packets hold the hanger in vertical position. The packets are ejected singly from a stack, the lower one being forced out through the discharge opening D after which the entire stack falls to the succeeding position after the withdrawal of the ejector to be described. After all the packets of the stack have been ejected, the unsupported hanger, as indicated in Fig. 2, swings to the rear, dislodging one of the standing packets, which packet falls flat in the compartment to be ejected. The hanger, when the first packet is released, swings front and, engaging the second package drops said packet to the bottom of the compartment for ejection, thus disposing of the entire number of packets in the compartment.

Each compartment is provided with an ejector mechanism for pushing or shoving the bottom packet through the discharge opening. This mechanism comprises a horizontally disposed, reciprocating ejector 12 which is preferably a hollow metal tube guided in a complementary casing or tube 13 having an upturned stop 13' at the rear

end for the ejector. In the top of the ejector guide is arranged a longitudinally extending slot 14 for the accommodation of an arm 15 of a bell crank lever which is pivoted or loosely connected at 16 with the ejector 12.

The series of bell crank levers may be pivoted on a single pivot rod as 17 extending throughout the length of the casing or housing 3, and each lever is provided with a retracting spring 18 suspended between the housing and the arm 15 to return the ejector and normally hold it in retracted position.

The second arm 19 of the bell crank lever is normally disposed in horizontal position and is depressed by pressure on the button 65 or key 20 at the upper end of the vertically arranged depressing rod 21 which is pivoted at 22 within the housing, to the arm 19. The rod passes through an opening 23 in the top of the housing and provision is made for the swinging movement of the bell crank lever and depressing key and rod.

It will be obvious that by depressing a selected key the clerk may, through the action of the complementary bell crank lever 75 and its ejector, push the desired packet through the discharge opening. When pressure is released from the key the spring 18 pulls the bell crank lever from dotted position in Fig. 2 and retracts the ejector.

Having thus fully described my invention, what I claim as new and desire to secure by Letters Patent is:—

In a dispensing cabinet the combination with a partition terminating below the top of the cabinet, of a packet hanger comprising a plate having a bottom supporting flange, and a suspending hook at the upper end of said plate projecting at right angles to the flange for pivotal support on the partition, said hook being offset from the plate to insure a swinging movement of the plate when the latter is unsupported from the rear, for the purpose described.

In testimony whereof I affix my signature.

SVERRE R. SVENDSGAARD.
